US0D1101509S

(12) **United States Design Patent** (10) **Patent No.:** **US D1,101,509 S**
(45) **Date of Patent:** **** Nov. 11, 2025**

(54) **CONTAINER**

(71) Applicant: **STASHER, INC.**, Emeryville, CA (US)

(72) Inventor: **Angelo Carpinelli**, Emeryville, CA (US)

(73) Assignee: **STASHER, INC.**, Emeryville, CA (US)

(**) Term: **15 Years**

(21) Appl. No.: **29/855,715**

(22) Filed: **Oct. 6, 2022**

(51) LOC (15) Cl. **09-07**

(52) U.S. Cl.

USPC **D7/629**

(58) **Field of Classification Search**

USPC D7/629; D3/205, 243, 289; D28/82-83

CPC A45C 11/00; A45C 11/008; A45C 13/02;

A45C 13/103; B32B 37/182

(57) **CLAIM**

The ornamental design for a container, as shown and described.

DESCRIPTION

FIG. 1 is an isometric view of a top, front, and right side of an ornamental design for a container;

FIG. 2 is an isometric view of a bottom, rear, and left side of the container of FIG. 1;

FIG. 3 is a front elevational view of the container of FIG. 1; FIG. 4 is a rear elevational view of the container of FIG. 1; FIG. 5 is a left side elevational view of the container of FIG. 1;

FIG. 6 is a right side elevational view of the container of FIG. 1;

FIG. 7 is a top plan view of the container of FIG. 1; and, FIG. 8 is a bottom plan view of the container of FIG. 1. The dash-dash-dash lines are included for the purpose of illustrating portions of the container that form no part of the claimed design. The dash-dot-dash lines are included for the purpose of illustrating boundary lines and form no part of the claimed design.

1 Claim, 8 Drawing Sheets
